UNITED STATES PATENT OFFICE

RUDOLPH J. SAILER, OF TOWNLEY, NEW JERSEY, ASSIGNOR TO THE SINGER MANUFACTURING COMPANY, OF ELIZABETH, NEW JERSEY, A CORPORATION OF NEW JERSEY

HEMMER

Application filed June 5, 1929. Serial No. 368,592.

This invention relates to a folder for use with sewing machines for forming a facing-strip upon the edge of a body-fabric of a shirt. Facing-strips are overlapping reinforcements customarily formed upon adjacent front portions of a shirt or other garment and upon one of these facing-strips buttons are secured which are adapted to enter buttonholes formed in the other facing-strip for closing the front of the shirt or garment.

The object of the present invention is the construction of a folder whereby the facing strip is formed upon the marginal portion of a body-fabric without the use of a separate fabric-strip.

According to the present invention the folder is constructed with a plurality of superposed guideplates with a tuck-forming channel at one side for forming a reentrant fold in the body of a fabric-section, back from its edge, and a hem-forming scroll at the other side, opposed to the tuck-forming channel, for turning under and directing the marginal portion of the fabric-section into the reentrant fold made by the tuck-forming channel for concealment of the raw edge of the fabric.

The invention is illustrated in the accompanying drawings in which Fig. 1 is a plan view of the folder attached to the cloth-plate of a sewing machine. Fig. 2 is a side-elevation of the folder showing it in operative relation to the needle and presser-foot of the sewing machine. Figs. 3 and 4 are sectional elevations, on an enlarged scale, on lines 3-3 and 4-4, respectively, of Fig. 1 and Fig. 5 is a diagrammatic view illustrating the work produced by the folder.

The folder is shown mounted upon a sewing machine having any suitable stitch-forming mechanism in which a pair of spaced needles 1 operate through needle-holes 2 in a presser-foot 3 above a throat-plate 4 carried by the cloth-plate 5. A feed-dog 6 operates in slots (not shown) in the throat-plate as will be understood by those skilled in the art.

The base-plate 7 of the folder is provided with an elongated slot 8 receiving a pair of

screws 9 by which it is secured to the cloth-plate 5 and by means of which the folder may be adjusted transversely to the direction of feed.

Secured to the base-plate 7 by soldering or otherwise, is the curved portion of a hem-scroll 10 having laterally extending and spaced guide-plates 11 and 12. At the delivery end of the folder the edge of the upper guide-plate 11 farthest from the base-plate 7 is turned downwardly and inwardly beneath the under guide-plate 12 forming a curved fold-guide 13 of a tuck-forming channel. Disposed between the upper and under spaced guide-plates is an intermediate arbor or guide-plate 14 which extends throughout the length of the folder and at its delivery end is also turned downwardly and laterally and parallel with and spaced from the upper guide-plate 11 and fold-guide 13. Adjacent the fold-guide the intermediate guide-plate 14 merges into the lower guide-plate 12 from which it extends downwardly and laterally in a reverse direction beneath and spaced from the fold-guide 13 terminating in the fabric-supporting plate 15.

It will be observed by reference to Fig. 3 that the superposed and spaced guide-plates 11, 12 and 14 at the fold-guide 13 constitute a tuck-forming channel for forming a reentrant fold in the body of a fabric-section *f* which fold receives the marginal portion *m*, the edge of which is turned back and directed toward the reentrant fold by the spaced guide-plates 11, 12 and 14 at the hem-scroll 10, all as represented diagrammatically in Fig. 5.

From the foregoing description it will be seen that the folder comprises the base-plate 7, the hem-scroll 10 sustained thereby and the tuck-forming channel-member of S-shaped cross-section having its intermediate limb 15" sustained by the free edge of the lower scroll member or guide-plate 12. The upper scroll member, constituting the guide-plate 11, has its free marginal portion downwardly and inwardly turned to form a lip 13 entering the space between the limbs 15 and 15".

It is understood, of course, that the fabric after being properly folded passes directly

from the folder to the stitching mechanism where it is secured by two parallel lines of stitches the position of which is denoted by the dotted lines s, s in Fig. 5.

5 Having thus set forth the nature of the invention, what I claim herein is:—

1. A folder comprising a fabric-supporting plate, a wall overhanging and sustained by one edge of said fabric-supporting plate, 10 an arbor spaced above and supported by said overhanging wall and extending laterally beyond said edge of the fabric-supporting plate and a hem-scroll embracing said arbor and having a free edge disposed between said 15 fabric-supporting plate and said overhanging wall.

2. A folder comprising a base-plate, a guiding-plate of S-shaped cross-section, and a hem-scroll sustained at one side by said 20 base-plate with one of its free edges affording a support for the intermediate limb of the S-shaped guiding-plate and its other free edge being spaced between the lower and intermediate limbs of said S-shaped guiding- 25 plate.

3. A guide for sewing machines comprising a base-plate, a hem-scroll secured at one side to said base-plate and a tuck-forming channel-member carried by the other side of 30 said hem-scroll remote from said base-plate.

In testimony whereof, I have signed my name to this specification.

RUDOLPH J. SAILER.
